UNITED STATES PATENT OFFICE

ANTOINE FRANCE, OF LIEGE, BELGIUM.

MINERAL-WASHING PLANT.

Application filed June 9, 1922. Serial No. 567,208.

To all whom it may concern:

Be it known that I, ANTOINE FRANCE, a subject of the King of the Belgians, residing at Liege, Belgium, 17 Quai Saint Leonard, have invented certain Improvements Relating to Mineral-Washing Plants, of which the following is a specification.

The present invention relates to the improvements in mineral washing plant and more particularly in wet sorting apparatus of the kind comprising flooded sorting pockets depending from a launder wherein the materials are subjected to the action of a conveying water stream, and having a hopper-like separation chamber formed in the upper portion thereof by a sloping screen leading downwardly to a discharge mouth, and means for supplying water in upward streams through said pockets, such as described and claimed in applications for U. S. A. Letters Patent Ser. Nos. 144,796 and 372,932, and the object of the invention is to obtain, in sorting apparatus of the type referred to, the separation of the products of higher specific gravity (or schists) and of the products of low specific gravity (or clean coal) by means of an upward stream of a velocity reduced to the minimum possible whatever the size of the particles to be separated, the raw product itself having been subjected to a preliminary classification according to specific gravity in a launder of suitable section and inclination by means of a so-called "horizontal" conveying stream, in order to differentiate it from the upward stream of the sorting apparatus proper.

The size of the material of higher specific gravity which can be sorted in the plant indeed depends from the velocity of this stream, and it will be easily understood that the possibility of reducing such velocity results in allowing the use of wet sorting apparatus of the type referred to above for the treatment of particles starting from a size which will be so much the more reduced that the aforesaid reduction of velocity may be more important.

Consequently as in this washing process the principles of equivalence enter into account only to a very small extent in the accidental moments when of the two kinds of streams employed, the upward stream plays the most important part while the part played by the conveying stream of the

launder is only secondary, if it becomes possible practically to do away with such accidents, it would become possible to treat completely in a single washing launder all minerals from about $\frac{1}{30}$ of an inch up to the size of about 3 inches generally considered as the maximum size in the case of coal treatment.

Now, as will be explained hereunder, it is not doubtful that the depth of the sorting pocket of the aforesaid wet sorting apparatus can play a capital part in attaining the result in question.

The present invention allows the modification of the said depth of the sorting pocket, and with this object in view, it comprises the provision of an oscillating sector-shaped discharge flap which can be adjusted at will in a suitable direction, and of means for effecting such adjustment and for maintaining the flap in any required position, in conjunction with the provision of means whereby the position of the sloping screen of the sorting pocket, leading to the aforesaid flap, may be adapted to the different adjusted positions given to the latter.

In order that the invention may be readily understood, certain embodiments of the said invention are, by way of example only, illustrated by the accompanying drawing, wherein:

Figs. 1 and 2 are respectively a vertical section in the plane of the longitudinal axis of the launder and a corresponding transverse section showing a wet sorting apparatus with oscillating discharge flap provided with a device for the modification of the depth of the sorting pocket according to the invention in one of its embodiments.

Fig. 3 is a diagram showing an arrangement comprising a plurality of wet sorting apparatus 20, 20', 20'', arranged in battery formation along a single launder 21 and connected to a common tank 22 for the reception of the discharged products of higher specific gravity, hereafter called "schists," each sorting apparatus being provided with a device for the modification of the depth of the sorting pocket according to the invention.

Fig. 4 is a diagram showing an arrangement comprising two wet sorting apparatus 25, 25', depending from two different launders 26, 26', and connected to a single tank 27 for the reception of the discharged

schists, each sorting apparatus being also provided with a device for the modification of the depth of the sorting pocket according to the invention.

5 Referring to Figs. 1 and 2, it will be seen that the shaft 1' of the oscillating flap 1 of the sorting apparatus has its ends supported in slides 6, the said shaft 1' being actuated by means of the operating lever 10 or the like so as to impart to the flap the required oscillatory movement. The slides 6 are at their upper end provided with an extension under the form of a rack 6' so that they can be adjusted, together with the 15 flap which they support, by means of the spur pinion 10 and the hand operated crank 4. A pin inserted both in a hole of the upper lateral wall of the apparatus and in one of a series of holes provided for the 20 purpose in a disc 5 secured on the shaft of the pinion 10, prevents the flap from dropping once it has been placed in the desired adjusted position. The lower portion or 25 screen plate 7 of the inclined screen of the sorting pocket is secured to the slides 6 and therefore moves solidly with the latter in the vertical direction, while a screw thread and spring device 9 allows the adjustment of the upper portion or screen plate 8, bent 30 back on the bottom of the launder, according to the various adjusted positions of the lower portion or screen plate 7 resulting from the adjustment of the flap.

It is obvious that instead of being capable 35 of adjustment in a vertical direction the shaft 1' of the flap might as well be adjusted obliquely.

It will be seen that by giving the flap a 40 higher or lower position it will be possible to reduce or to increase the depth of the sorting pocket. As stated above, this depth plays a capital part in the operation of the apparatus. Indeed, the importance of the 45 thickness of the mass of schists in the sorting pocket, which the upward stream has to cross, acts to a certain extent to compensate the irregularities in the velocity of the said stream so as to create at the upper surface of the layer of schists a zone of ideal sorting 50 with an upward stream of almost no velocity but however sufficient to prevent, in the case of coal treatment, the larger sized coals to settle together with the schists, and on the other hand to make it possible for the smaller schists to settle. The accumulation of 55 schists in the sorting pocket constitutes moreover a kind of governor of which the importance in the working of the process may be increased by means of the device forming 60 the subject matter of the present invention. Indeed, this governor makes it possible to obtain an intermittent discharge of the schists through the medium of the oscillating flap while in the upper portion of 65 the sorting pocket the surface of the accumu-

lated schists may remain almost uniformly in alignment with the level of the layer of schists in the launder both upstream and downstream in relation to the sorting apparatus under consideration. As any irregularity in the level of such layer of schists in the locality of the apparatus has to be corrected by an increase in the velocity of the upward stream, it is obvious that if the said irregularity is practically suppressed, such exaggeration of the velocity of the upward stream in order to avoid the consequences of the irregularities referred to also becomes unnecessary.

70 Although it is possible in these conditions to treat at the same time the whole of the raw material, without previously classifying same according to volume, certain circumstances mainly of commercial order, may render desirable the treatment of categories 75 separated according to volume before washing.

Such is for instance the case in the treatment of coal where the problem does not generally consist in eliminating absolutely 90 the whole of the schists, but where all categories are characterized by a certain tolerance as to the ash contents of the finished products.

95 In such conditions it is obvious that it is desirable to treat separately the categories which are essentially differentiated from each other as to the degree of purity.

Now, it has been observed, and this is a remarkable advantage of the invention, that the device which forms the subject matter of the latter and of which the principle has been described above, provides a solution to the very delicate problem of the connection 100 to the same tank for the reception of the discharged schists of a plurality of sorting apparatus depending from a single launder as illustrated by Figure 3 or from different launders as illustrated by Figure 4.

105 Heretofore, such problem has been solved by placing the apparatus connected to the same tank at slightly different levels and by providing in the channels for the discharge of the schists devices adapted to prevent any exchange of water between one apparatus and the other.

110 Now, the accumulation of schists above the flap to a thickness which may, as illustrated by Figs. 3 and 4 wherein the shaded portions represent the layer of schists, be varied at will by providing in each sorting apparatus the device for the modification of the depth of the sorting pocket according to the invention, constitutes a real means for adjusting the effective cross sections of 115 the channels for the evacuation of schists which form between them communicating vessels, and such means makes it thus possible to avoid absolutely any exchange of 120 water between the various sorting appa- 125

ratus of which each can therefore be subjected to a constant and absolutely perfect adjustment.

Indeed, the accumulation of schists above the flap being in each apparatus constituted by schists of clearly determined size to a thickness which can when the apparatus is in operation be considered as practically constant, it may be stated that the effective section for the passage of the water stream through the interstices of the mass of schists can itself be practically perfectly constant and therefore capable of perfect adjustment.

It should be understood that the invention is not restricted to the embodiments illustrated and that the means employed to effect the adjustment of the flap, for instance, may vary according to the needs of each individual case as well as the details of construction and arrangement of the apparatus, without the principles of the invention, as defined in the appended claims, being affected thereby.

25 I claim:

1. In wet-sorting apparatus of the kind comprising a flooded sorting pocket depending from a launder and having a hopper-like separation chamber formed in the upper portion thereof by a sloping screen leading downwardly to a discharge mouth, and means for supplying water in upward streams through said pocket, the combination of: a sloping screen formed of two independent substantially aligned screen-plates; a movable sector-shaped discharge flap on a pivoted shaft extending horizontally along the lower edge of the screen and projecting at one end through the corresponding wall of the pocket; means on the said projecting end of the shaft for imparting an oscillatory movement to the flap; a pair of suitably guided vertically movable supporting members for the said shaft and the lower screen-plate, arranged within and adjacent the lateral walls of the pocket; hand-operated means in positive engagement with said supporting members for adjusting the position of same, whereby the

depth of the separation chamber above the flap may be varied; means for securing the aforesaid supporting members in any adjusted position; and spring pressed means for causing the adjustment of the upper-screen-plate in relation to the lower screen plate; substantially as described.

2. In wet-sorting apparatus of the kind comprising a flooded sorting pocket depending from a launder and having a hopper-like separation chamber formed in the upper portion thereof by a sloping screen leading downwardly to a discharge mouth, and means for supplying water in upward streams through said pocket, the combination of: a sloping screen formed of two independent substantially aligned screen-plates; a movable sector-shaped discharge flap on a pivoted shaft extending horizontally along the lower edge of the screen and projecting at one end through the corresponding wall of the pocket; means on the said projecting end of the shaft for imparting an oscillatory movement to the flap; a pair of suitably guided substantially vertical slides carrying the said shaft and extending within the pocket adjacent the lateral walls thereof, said slides moreover having the lower screen-plate rigidly secured thereto; integral rack extensions at the upper end of said slides; a pair of pinions positively engaging said racks, on a shaft extending transversely across the launder over the pocket and fitted outwardly with a crank-handle; a disk having a circumferential series of holes therein, secured outwardly on the last-named shaft adjacent the corresponding side of the launder; and a pin for securing said disc in position through engagement in both a suitable hole of said slide of the launder and one of the holes in the disc.

In testimony whereof I signed hereunto my name in the presence of two subscribing witnesses.

ANTOINE FRANCE.
